UNITED STATES PATENT OFFICE.

STACY OLIVER, OF HARTFORD, CONNECTICUT.

AUTOMATIC RIFLE.

1,383,966.

Specification of Letters Patent.

Patented July 5, 1921.

Application filed February 3, 1919. Serial No. 274,689.

To all whom it may concern:

Be it known that I, STACY OLIVER, a citizen of the United States, residing at Hartford, in the county of Hartford and State 5 of Connecticut, have invented certain new and useful Improvements in Automatic Rifles, of which the following is a specification.

This invention relates to automatic rifles 10 of the type wherein the bolt is projected or retracted by the force of the recoil from the discharge of a cartridge, during which reTRACTING movement of the bolt and firing pin, the spent shell is extracted and ejected 15 from the gun and the new cartridge placed in position for feeding into the cartridge carrying chamber of the rifle and also during which recoil movement the hammer of the rifle is cocked, completing, when the 20 bolt is moved forward by the recoil spring, the operation of the rifle for discharge.

An object of this invention is to provide, 25 at the breech of the barrel thereof, which cartridge chamber is engaged by a pair of spring hook members for moving the cartridge chamber rearwardly a short distance upon the retraction action of the bolt of the 30 rifle to allow the bullet from the discharged cartridge to pass out of or practically pass out of the barrel prior to the exhaust of the gases from the free end of the barrel resulting in the utilization of the entire projecting force of the gases for propelling the 35 bullet; to provide means for limiting the outward or reTRACTING movement of the bullet chamber and also to provide means for returning it to its normal position in 40 engagement with the breech end of the barrel after it has reached the limit of its reTRACTED movement.

Another object of the invention is to provide a relatively simple hammer mechanism 45 and trigger mechanism for operating and controlling the operation of the hammer as well as to provide a safety lever which is carried by the trigger and is adapted to engage the hammer to relieve the firing pin of the pressure of the hammer and hammer 50 spring when the rifle remains idle and also to eliminate liability of accidental discharge of the rifle in case the hammer should be accidentally operated in any other manner

than through or by the operation of the 55 trigger and its companion mechanism.

Other objects of the invention will appear in the following detailed description taken in connection with the accompanying drawings, forming a part of this specification 60 and in which drawings:

Fig. 1 is a fragmentary longitudinal section through the rifle showing the same in position for firing.

Fig. 2 is a fragmentary longitudinal section showing the sliding bolt and cartridge chamber in elevation and also showing these members starting a retarding action.

Fig. 3 is a fragmentary longitudinal section through the rifle showing the bolt reTRACTED and the cartridge chamber in position for receiving a new or unexploded cartridge.

Fig. 4 is a fragmentary section of the rifle illustrating the means for automatically locking the bolt in a reTRACTED position when the supply of cartridges from the magazine has been exhausted.

Fig. 5 is a fragmentary longitudinal section taken on the horizontal plane through 80 the breech end of the barrel and the cartridge chamber illustrating the means for returning the cartridge chamber to its operative position.

Fig. 6 is a fragmentary sectional view 85 taken on a vertical plane through the cartridge chamber and the forward end of the sliding bolt illustrating the connection between the bolt and the cartridge chamber.

Fig. 7 is an end elevation of the cartridge 90 chamber, and

Fig. 8 is a fragmentary view of the hammer and trigger mechanism of the rifle, illustrating the operation of the safety lever for holding the hammer away from the 95 firing pin to relieve the firing pin of the pressure of the hammer spring.

Referring more particularly to the drawings, wherein like characters indicate like and corresponding parts throughout the 100 several views, 1 indicates the barrel of the rifle, the rear or breech end of which engages into the receiver 2. This receiver 2 comprises the frame which carries the operating mechanism of the rifle, and it also 105 carries a barrel screw 3 which extends diagonally through the forward projecting lower end of the receiver and engages in a

notch 4 formed in the barrel for connecting the barrel to the receiver. The usual type of hand guard 5 is mounted over the portion of the receiver carrying the barrel screw 3 and engages the under surface of the barrel 1.

The receiver 2 carries a cartridge chamber 6 the forward end of which abuts the free end of the barrel 1 when in a cartridge carrying position, as shown in Figs. 1 and 3 of the drawings. This cartridge chamber 6 is provided with a pair of diametrically opposed notches 7 formed at its rear end in which notches the hook ends 8 of the flat springs 9 engage. The flat springs 9 are carried by the bolt 10 of the rifle which is retracted by the recoil of the gases from an exploded or discharged cartridge. When the bolt 10 moves rearwardly under action of the gases in the exploded cartridges, the hooks 8 engaging in the notches 7 will draw the chamber 6 rearwardly with the movement of the bolt, permitting the bullet to pass practically entirely out of the barrel 1 prior to the exhaust of the gases through the breech end of the rifle, thereby allowing utilization of the maximum projecting force of the exploded gases in the cartridge, for propelling the bullets. The rearward movement of the chamber 6 is limited by the chamber stop screw 11 carried by the receiver 2 and engaging in an elongated recess 12 in the lower portion of the chamber. When the chamber reaches the limit of its rearward movement, the pressure or rearward pull of the bolt 10 upon the hooks 8 will cause them, owing to the resiliency of the springs or arms 9 to slip out of the notches 7 disconnecting the bolt and the chamber. The chamber 6 is then returned to its normal position so that its forward end will engage the breech end of the barrel 1 by spiral springs 13 which are coiled about bolts 14 threaded into the breech end of the barrel 1 and extending through the chamber 6, at diametrically opposed points and substantially at 45° from the notches 7. The springs 13 are seated in relatively large recesses in the chamber and their outer or forward ends engage against the inner ends of the recesses, while their rear ends engage against the heads 15 of the bolts 14. These springs are compressed, during the reTRACTING movement of the chamber 6 and when the chamber is released from connection with the hooks 8, the springs 13 expand to return the chamber to the cartridge receiving position as shown in Fig. 3 of the drawings.

The chamber 6 is also provided with a recess 16 in its rear end which opens into the bore 17 of the chamber and is adapted for receiving the cartridge rim engaging end 65 of the extractor 18 which is carried by the

bolt 10 for extracting the shell of a spent cartridge during the retracting action of the bolt. After the shell has been extracted from the chamber 6 and the chamber has returned to its normal position, the shell is ejected from the receiver 1 by any preferred type of ejector, indicated at 19 in Fig. 4 of the drawings.

The bolt 10 moves longitudinally in the bore 19 formed in the receiver 2 and it is provided with a central or axial bore in which the firing pin 20 is slidably mounted. A recoil spring 21 is positioned within the receiver 2 and partially within the bolt 10, being coiled about the firing pin 20. The forward end of the recoil spring 21 engages the shoulder formed by the reducing of the bore of the bolt 10 while its rear end engages against the rear end 22 of the receiver 2, this spring returns the bolt to its forward position after the recoil of the cartridge has spent itself. The bolt 10 is provided with an opening communicating with the axial bore and through the forward end of the bolt which receives the striker end 23 of the firing pin which engages a cartridge as indicated at 24 for exploding the cartridge when the firing pin is operated by the operation of the hammer as will be hereinafter specifically described. The spring 25 is carried within the bolt 10 and engages the forward end of the firing pin 20 to hold the striker end 23 thereof out of engagement with the cartridge in the chamber 6.

The receiver 2 is provided with a well or magazine 26 in which a follower spring 27 is placed, this follower spring 27 is preferably a flat spring sinuously bent and the cartridges in the well rest upon the uppermost length of this spring, they being forced or urged upwardly by the expanding action of the spring so that when the bolt 10 reaches the rearward limit or the limit of its reTRACTED movement, and the shell of the spent or discharged cartridge has been ejected, a new cartridge will be forced into alignment with the bore 17 of the chamber 6 and held in proper position by cartridge stops 28 until the springs 21 return the bolt 10 which returning movement of the bolt will force the uppermost cartridge as shown in Fig. 3, into the bore 17 and the chamber 6 where it will be in position to be discharged by actuation of the firing pin 20 through the medium of the hammer of the rifle.

The terminal of the follower spring 27 is returned or bent downwardly and laterally as shown at 29, forming a lip for engagement with the laterally extending lug 30 formed upon the bolt locking lug 31. The locking lug 31 is slidably mounted in the receiver 2 and is normally held in a downward or retracted position by a contracting spiral spring 32. When the last cartridge has been fed from the well or magazine 26,

the end 29 of the follower spring 27 will engage the lip 30 and force the locking lug 31 upwardly so that its upper end will engage in a recess 33 formed in the bolt 10 to lock the bolt in a retracted or rearward position as clearly shown in Fig. 4 of the drawing, thereby preventing the automatic closing of the breech of the rifle when the same is not loaded. If it is desired to close the breech or allow the bolt 10 to move forwardly without the placing of a cartridge in the chamber 6, the spring 27 may be manually forced downwardly to allow the lug 31 to fall sufficiently to disengage it from the notch 33 after which the bolt 10 will be returned or moved forwardly by the expanding action of the recoil spring 21.

The receiver or frame 2 is provided intermediate its ends with the recoil block 34 slidably disposed beneath the firing pin 10 and vertically movable within the receiver. The block 34 is vertically slotted and held in place by a pin 35 passing through the slot and against which an expansion spring 36 bears. The spring 36 urges the block 34 upwardly. The upper face of the block 34 has near its forward edge an abrupt inclined shoulder adapted to bear against the shoulder or depressing lug 37 of the bolt 10 to take up to a large extent the recoil of the bolt when the cartridge is fired or exploded. The rear portion of the upper face or end of the block 34 has an elongated cam face adapted to engage the projection or shoulder 37 and yieldably retard the forward advance of the bolt subsequent to its recoil. The block 34 thus absorbs shock incident to the retraction of the bolt, and also retards the forward thrust of the bolt in feeding the cartridges to the firing chamber.

A stop pin or anvil 38 is carried by the frame or receiver 2 and engages the under surface of the bolt 10. The stop 38 is adapted to strike the depending lug or shoulder 37 on the bolt 10 when the latter is moved into its forward position.

The firing pin 20 has a knurled head 39 upon its rear end and it is also provided with a hammer engaging rounded portion 40 which is engaged by the striking face 41 of the hammer 42. The hammer 42 is pivotally mounted upon a suitable pin 43 carried by the frame or receiver 2 of the rifle and it is provided with a cut out portion extending inwardly from its rear edge. A suitable lug 44 is connected to the hammer and projects upwardly into the said recess, being engaged by the forward free end of the hammer spring 45. The hammer spring 45 extends rearwardly into a suitable recess formed in the stock 46 of the rifle, being connected to the frame 2 by a suitable bolt or set screw 47. The spring 45 normally urges the hammer 41 forwardly

into a striking position with respect to the firing pin 20 and the hammer is held in a cocked position by a sear 48 which is pivotally mounted upon a pin 49. The sear 48 has a lip 50 which engages over the upper edge of the shoulder which forms the lower wall of the recess 51 into which the free end of the hammer spring 45 extends, for holding the hammer in a cocked position. The sear 48 is urged into a position for engagement with the said shoulder by a spiral spring 51. The sear 48 is further provided with a shoulder 52 upon its forward corner and this shoulder is engaged by the upper end of a flat spring 53 which is carried by the trigger 54. The trigger 54 is pivotally mounted upon a pin 55 carried by the frame 2 and the finger strip 56 thereof projects outwardly out of the frame 2 as is ordinary in trigger constructions, it being guarded or surrounded by a suitable trigger guard 57.

The trigger 54 is normally urged forwardly by the trigger spring 58, one end of which is connected to the trigger 54 and the other end to a pin 59 carried by the frame or receiver 2.

A safety lever 60 is pivotally connected as shown at 61 to the trigger 54 and it is provided with an upwardly extending substantially straight portion 62 which engages against the shoulder 63 formed upon the receiver or frame 2 at the rear end of the same. The safety lever 60 is normally held in engagement with the shoulder 63 by the spring 64 which is connected to the lever and to the pin 59. The rear edge of the lever at its upper end is beveled as shown at 65 and this beveled edge is provided for engagement against a downwardly facing shoulder 66 formed upon the hammer 42, as shown in Fig. 8 of the drawings to hold the striking face 41 of the hammer out of engagement with the end 40 of the firing pin to release the firing pin of the pressure of the hammer and the hammer spring 45 and also to prevent accidental discharge of the rifle in case the hammer 42 should be jarred loose from a cocked position, during the handling of the rifle. The safety lever 60 is connected to the trigger 54 in such manner that when the trigger is moved rearwardly upon its pivot 55, for releasing the hammer 42 from the restraining action of the sear 48, the lever will be moved downwardly along the shoulder 63 sufficient distance to move it out of the path of the shoulder 66, allowing the striking face 41 of the hammer to strike the end 40 of the firing pin 20 and longitudinally displace the firing pin for discharging the shell or cartridge placed in the cartridge chamber 6.

A guard 70 is connected to the frame or receiver 2 and guards the firing pin and the hammer and the thumb rest 67 thereof, and

also the protruding end of the firing pin 20 and its knurled head 39 to prevent accidental operation of either of these members by their coming in contact with or setting 5 upon an article.

The receiver 2 carries any ordinary or preferred type of rear sight 71 while the barrel 1 carries any preferred type of front sight 72.

- 10 Summing up, the operation of the automatic rifle is generically as follows: In the initial charging or filling of the well or magazine 26 with cartridges it is necessary to cock the hammer 42 and force down the 15 plunger 34, by means of a button on the outside of the frame or receiver 2, and manually withdraw or retract the bolt 10 by pulling rearwardly upon the firing pin 20. The bolt 10 is connected to the firing pin 20 20 by a pin 74 which extends diametrically through the firing pin, at the forward end of the same, being seated in an elongated slot 75 to permit limited movement of the firing pin independently of the bolt 10.
- 25 After the magazine or well 28 has been filled with the cartridges 24 and one of the cartridges has been properly positioned for forcing into the chamber 6, the bolt 10 is released and the spring 21 will move the 30 bolt forwardly forcing the cartridge into the chamber 6. The retracting movement of the bolt 10 and firing pin 20 will force the hammer 42 into a cocked position, where it will be held by the engagement of the 35 lip 50 of the sear 48 upon the upwardly facing shoulder formed by the recess 51. The hammer 42 will be relieved from the restraining action of the sear 48 when the trigger 54 is moved rearwardly upon its 40 pivot, rocking the sear to move the lip 50 out of engagement with the said shoulder when the hammer spring 45 will force the hammer 42 forwardly, causing it to impact against the end 40 of the firing pin 20 to 45 discharge the cartridge 24. The recoil of the cartridge will force the bolt 10 rearwardly and during the initial rearward movement of the bolt, the cartridge chamber 6 will be moved therewith, allowing the 50 bullets or projectiles to pass substantially entirely out of the barrel 1 prior to the release of the gases from the breech end of the rifle. When the chamber 6 has moved the limit of its rearward movement as regulated by the chamber stop screw 11, the hook 8 will move out of engagement with the notches 7 allowing the springs 13 to expand and return the chamber 6 to its normal position, during which movement and 55 the further rearward movement of the bolt 10, the shell of the said cartridges will be extracted from the chamber 6 by the extractor 18 and ejected by the ejector 19. Upon the ejection of the shell of the spent 60 cartridge the new cartridge will be forced 65

by the follower spring 27 into alignment with the bore of the chamber 6, so that it will be forced therein by the return or forward movement of the bolt 10. The rearward movement of the bolt 10 and firing 70 pin 20 carried thereby will set the trigger and hammer mechanism, in position to discharge the cartridge last forced into the bore of the chamber 6 when the trigger 54 is moved rearwardly. The above cycle of 75 operation is repeated upon each discharge of the rifle.

Changes in details may be made without departing from the spirit of the invention, 80 but;

I claim:

1. In an automatic rifle, in combination, a barrel, a cartridge chamber, means for feeding cartridges into alignment with said chamber, a recoil operated bolt for forcing cartridges into said chamber, yieldable means carried by the bolt for interlocking engagement with said chamber for connecting the chamber to the bolt for retracting the chamber when the bolt is retracted, 90 means for limiting the retraction of the chamber and releasing the same from said bolt whereby said chamber is adapted to move with the bolt through a predetermined retracting distance, and means carried by the 95 chamber and connected to said barrel for returning the chamber to a bullet receiving position.

2. In an automatic rifle, the combination of a barrel, a cartridge chamber, means for feeding cartridges into said chamber, yieldable means carried by the bolt adapted for interlocking engagement with the chamber for retracting the same with the bolt, means for releasing the chamber from the bolt 100 when the chamber is retracted through a pre-determined distance, means for returning the chamber to a bullet receiving position, and means carried by the bolt for extracting the spent shell from the chamber 110 after the retracting movement of the chamber has been arrested.

3. In an automatic rifle, the combination, of a barrel, a cartridge chamber, means for feeding cartridges into alignment with said chamber, a recoil operated bolt for forcing cartridges into said chamber, said chamber provided with a pair of recesses in its rear end, a pair of flat springs carried by said bolt and having hooked end portions adapted 115 to engage in said recesses for connecting the chamber and bolt to retract the chamber upon retraction of the bolt.

4. In an automatic rifle, the combination, of a barrel, a cartridge chamber, means for feeding cartridges into alignment with said chamber, a recoil operated bolt for forcing cartridges into said chamber, said chamber provided with a pair of recesses in its rear 125 end, a pair of flat springs carried by said 130

- 5 bolt and having hooked end portions adapted to engage in said recesses for connecting the chamber and bolt to retract the chamber upon retraction of the bolt, means for limiting the retracting movement of said chamber, said hook member adapted to disengage said recesses, whereby the chamber will move with the bolt for only a part of the retracting movement of the bolt.
- 10 5. In an automatic rifle, the combination, of a barrel, a cartridge chamber, means for feeding cartridges into alignment with said chamber, a recoil operated bolt for forcing cartridges into said chamber, said chamber provided with a pair of recesses in its rear end, a pair of flat springs carried by said bolt and having hooked end portions adapted to engage in said recesses for connecting the chamber and bolt to retract the chamber
- 15 upon retraction of the bolt, means for limiting the retracting movement of said chamber, said hook member adapted to disengage said recesses, whereby the chamber will move with the bolt for only a part of the retracting movement of the bolt, and means carried by the chamber and connected to said barrel for returning the chamber to a cartridge receiving position.
- 20 6. In an automatic rifle, the combination, of a barrel, a cartridge chamber, means for feeding cartridges into alignment with said chamber, a recoil operated bolt for forcing cartridges into said chamber, said chamber provided with a pair of recesses in its rear end, a pair of flat springs carried by said bolt and having hooked end portions adapted to engage in said recesses for connecting the chamber and bolt to retract the chamber
- 25 upon retraction of the bolt, means for limiting the retracting movement of said chamber, said hook member adapted to disengage said recesses, whereby the chamber will move with the bolt for only a part of the retracting movement of the bolt, and means carried by the chamber and connected to said barrel for returning the chamber to a cartridge receiving position.

STACY OLIVER.
